Inventor:

John D. McLean

UNITED STATES PATENT OFFICE.

J. D. McLEAN, OF NEW YORK, N. Y.

APPARATUS FOR FORMING STEREOTYPE MOLDS.

Specification forming part of Letters Patent No. 43,323, dated June 28, 1864.

To all whom it may concern:

Be it known that I, J. D. McLEAN of the city, county, and State of New York, have invented a new and Improved Machine for Forming Molds or Matrices for Producing Stereotype and Electrotype Plates for Letter-Press Printing; and I do hereby declare that the following is a full, clear, and exact description of the same, reference being had to the accompanying drawings, making a part of this specification, in which—

Figure 1 is a side sectional view of my invention, taken in the line $x-x'$, Fig. 2; Fig. 2, a plan or top view of the same, partly in section; Fig. 3, a transverse vertical section of the same, taken in the line $x'-x'$, Fig. 1; Fig. 4, an enlarged transverse section of the plates between which the dies work, taken in the same line $y-y'$ as Fig. 3; Figs. 5, 6, and 7, plan or top views of different dies.

Similar letters of reference indicate corresponding parts in the several figures.

The object of this invention is to obtain a machine of simple construction by which molds or matrices for producing stereotype or electrotype plates for letter-press printing may be formed direct from dies, thereby avoiding the labor and expense of setting up type and the casting or forming of molds therefrom.

To enable those skilled in the art to fully understand and construct my invention, I will proceed to describe it.

A represents a rectangular framing, which constitutes the base of the machine, and rests upon or is supported by four feet or knobs, a , one at each angle or corner.

On the end pieces of the framing A there are secured uprights b , two on each, to which the ends of two parallel plates, B B, are secured, and to the upper ends of these uprights a bar, C, is secured, said bar being directly over the plates B B and having a hub, c , at its center, in which a plunger, D, is fitted, said plunger having a knob, d , on its upper end and a spiral spring, e , upon it below the knob, the spring having a tendency to keep the plunger elevated to its fullest extent, as will be understood by referring to Figs. 1 and 3. The plates B B have each a groove, f , made vertically in them, said

grooves being in line with each other in a plane transversely with the plates.

E is a sliding frame composed of two bars, g , which are fitted between the plates B B, and have cross-arms h at their upper and lower ends, which are connected by rods i . This sliding frame E has a rod, F, connected to one of its bars, g , by means of a joint, j , said rod being between the plates B B and extending some distance beyond them with an upright, k , on its outer end, which may be fitted into any of a series of notches, l , in a horizontal bar, G, attached to the uprights b at one end of the framing A. (See, more particularly, Fig. 1.)

H represents a series of dies, which are fitted between the plates B B and within or between the bars g , g of the sliding frame E. These dies H have cross-arms m on their upper ends, which rest upon the upper edges of the plates B B and retain the dies between said plates.

The dies H consist of capitals and small letters, an alphabet of each, numerals, and punctuation-marks, and it will be seen that by moving the rod F the sliding frame E will be moved and with it the dies H.

I is a bed, the ends of which are fitted in rabbets n , n at the sides of the framing A, so as to move laterally therein, as indicated by the arrows 1, 2, shown in Fig. 2. To this bed I there are attached transversely two racks, J J, which are at the outer sides of the plates B B and parallel therewith, as shown in Fig. 2. In each of these racks a pawl, K, catches, said pawls being connected at their upper ends by pivots o with the lower ends of levers L, the upper ends of which are attached by fulcrum-pins p to the plates B B. The lower end of each lever L has a spiral spring, q , attached to it, one end of said springs being attached to the plates B, and a rod, r , projects horizontally from the lower end of each lever L, and has a spiral spring, s , attached to it, said springs being connected to the pawls K.

In each groove f of the plates B B there is fitted a slide, M, which rests on springs N N, as shown in Figs. 3 and 4.

On the bed I there is placed a sliding plat-

form, O, the latter being fitted between guides *t t* at the sides of said bed. To the under side of the platform O there is secured longitudinally a rack, P, with which a pawl, Q, engages. This pawl works on a pivot, u, and extends beyond the side of the bed I, and is curved at one side, as shown at *v* in Fig. 2.

R is a screw, which passes through a bracket, S, at one end of the framing A, as shown clearly in Fig. 2.

The operation is as follows: The material which is used for the mold or matrix is placed on the platform O. This material may be wax or any suitable plastic substance which will receive the impression of the dies H. The several dies, as required, are brought in line with or directly over the grooves f upon the slides M and underneath the plunger D by moving the rod F. The notches l in the bar G are all provided with letters to serve as an index for the operator, who places the lower end of the upright k in the notch l, which is provided with a letter corresponding to the one on the die, and which is to be impressed in the mold. When the die is adjusted over the grooves f, the operator forces down the plunger D, the latter forcing the die into the plastic substance on the platform. As each die is forced down the ends of its cross-arm m will come in contact with the levers L L and throw back the pawls K, which, when the die rises, are drawn back to their original position, and in consequence of catching into the racks J J move the bed I along a distance equal to the required spaces between the letters. When one line of impressions is made, the outer end of the pawl Q comes in contact with the screw R, and said pawl will consequently be actuated and the platform O moved in the direction indicated by arrow 3. This movement of the platform O determines the spaces between the lines of the impressions, and when one line of impressions is made the operator raises the pawls K by means of

projections a^x, attached thereto, and moves the bed I back to its original position for a succeeding line of impressions to be made.

The width of the spaces between the lines of impressions may be varied as required by means of the screw R, which may be adjusted more or less inward toward the pawl Q, so that the latter may be actuated in a greater or less degree.

The arms m of the dies H, at the outer sides of the plates B, vary in width according to the size of the die. This is necessary in order that the impressions be properly spaced.

The slides M M are designed to close the tops of the grooves f to admit of the arms m of the dies passing over them.

The pawl Q is provided with a spring to give it its return motion.

Having thus described my invention, what I claim as new, and desire to secure by Letters Patent, is—

1. The employment or use of a sliding frame, E, provided with type-dies H, in connection with parallel plates B B, a notched bar, G, and a rod, F, provided with an upright, k, all arranged as shown, for the purpose of adjusting the type-dies over the plastic substance which receives the impressions, for the purpose set forth.

2. The plunger D, in combination with the die-frame E, grooves f f in the plates B B, and slides M M in said grooves, for the purpose specified.

3. The pawls K K, connected with the levers L L, with the springs q s attached, in connection with the racks J J on the bed I, for the purpose specified.

4. The pawl Q and screw R, in connection with the pawl P at the under side of the platform O, for the purpose set forth.
